UNITED STATES PATENT OFFICE.

BERT BALL, OF ST. LOUIS, MISSOURI.

DESIGN FOR A HANDLE FOR SPOONS OR SIMILAR ARTICLES.

SPECIFICATION forming part of Design No. 35,882, dated April 29, 1902.

Application filed February 17, 1902. Serial No. 94,563. Term of patent 14 years.

To all whom it may concern:

Be it known that I, BERT BALL, a citizen of the United States, residing at the city of St. Louis, in the State of Missouri, have invented and produced a new and original Design for a Handle for a Spoon or Similar Article, of which the following is such a full, clear, and exact description as will enable any one skilled in the art to which it appertains to make and use the same, reference being had to the accompanying drawing, forming part of this specification.

My invention is shown in the drawing hereto attached, which represents the front or obverse side of the handle, the said handle being shown as connected at its lower end with the bowl of a spoon, said bowl being shown in dotted lines.

As shown in the drawing, the principal feature of my design consists in the decoration of the upper surface of the tapering handle of the spoon or other article. This decoration represents allegorically the progress of the Louisiana Purchase within the last one hundred years and is bordered by a scroll-work, which constitutes the outline of the handle. Near the lower or tapered end of the handle, above the bowl of the spoon, is shown a number of buffalo pursued by a mounted Indian huntsman. In the background is represented the setting sun. Next come a number of scouts or trappers, behind

them in the background being a range of mountains. Following them are two mounted scouts and a third scout in a kneeling position 35 kindling a fire. In the background behind them are woods, and in the foreground is represented a canoe, in which is a paddle. Following these is a hooded wagon or "prairie-schooner" drawn by four horses, the driver, 40 a pioneer, being mounted on one of the leaders. A second pioneer walks beside the wagon. Behind the wagon is a section of railway-track, upon which is a modern locomotive, and in the background the representation of a 45 city. The extreme upper end of the handle is formed of ornamental scrollwork, the chief feature of which is a plain broad band extending in a curved line across the upper end of the handle.

Having described my invention, what I claim as new, and desire to secure by Letters Patent, is—

The design for the handle of a spoon or similar article substantially as herein shown 55 and described.

In testimony whereof I have hereunto set my hand and seal in the presence of the two subscribing witnesses.

BERT BALL. [L. S.]
